No. 694,875.

Patented Mar. 4, 1902.

G. A. MEIGHAN.

BICYCLE SADDLE.

(Application filed Oct. 4, 1901.)

(No Model.)

UNITED STATES PATENT OFFICE.

GEORGE A. MEIGHAN, OF PROVIDENCE, RHODE ISLAND.

BICYCLE-SADDLE.

SPECIFICATION forming part of Letters Patent No. 694,875, dated March 4, 1902.

Application filed October 4, 1901. Serial No. 77,585. (No model.)

To all whom it may concern:

Be it known that I, GEORGE A. MEIGHAN, a citizen of the United States, residing in the city and county of Providence and State of Rhode Island, have invented certain new and useful Improvements in Bicycle-Saddles, of which the following is a specification.

My invention relates to a bicycle-saddle having three independent pads forming a seat, one of which pads is rigidly secured to the saddle-tree, and means mounted on the saddle-tree for giving lateral adjustment to the other two pads; and the object of my invention is to provide a saddle which shall readily yield to the movements of the rider in the manner as hereinafter described, and specifically pointed out in the claims.

In the accompanying sheet of drawings, Figure 1 represents a top plan view of the saddle and showing the pommel extended in dotted lines. Fig. 2 is an inverted view of the saddle. Fig. 3 is a longitudinal section of the saddle, taken in line xx of Fig. 1. Fig. 4 is a rear elevation view of the saddle. Fig. 5 is a top plan view of the saddle-tree as provided with means for giving adjustment to the seat-pads proper. Fig. 6 is a longitudinal central sectional view of one of the seat-pads.

Similar letters of reference indicate similar parts in the several views of the drawings.

Referring to Fig. 1, A represents the pommel-pad, and A' A' two movable pads which form the seat proper, and each of the three pads are constructed of yielding material and mounted upon the saddle-tree in the manner as specified later on.

B represents the saddle-tree as cast in one piece and adapted to extend in a horizontal position across the saddle-post, having a centrally-downward portion c, provided with a circular opening c', longitudinally disposed to receive the projecting arm p of the saddle-post, as indicated by dotted lines in Fig. 3, and the said portion c of the saddle-tree is further provided with two screw-threaded openings, transverse of the opening c', to receive clamping-bolts d d, which bolts hold the saddle-tree firmly in position upon the said arm p of the saddle-post. Each end portion of the saddle-tree turns upward, so as to form ears c² c², with an extension projecting outwardly

from each of said ears, as c³ c³; and each of the ears is provided with a circular opening of the same size and opposite to each other at a point c⁴ c⁴ to receive a bolt C, which is provided with a right and left hand screw-threaded portions, as at e e. This bolt extends parallel with the saddle-tree and is made to rotate in the same plane thereon by the circular collar 60 e', which is made secure to the said bolt by a pin e², having its peripheral edge to fit within a groove e³ of the saddle-tree.

A represents the pommel-pad, which consists of an inner layer of felt f and covered by two pieces of thin leather, as f' and f², respectively, both of which pieces are stitched together at the bottom edge of said felt f, as at a point g, and this pad is mounted upon a metallic arm D, having a projecting flange h to surround the side of the said pad, and the both members A and D are secured together by the screw-bolts i i, which engage with nuts placed between the bottom layer of leather f² and layer of felt f, respectively, in the manner as shown in Fig. 3. The arm D projects rearwardly from the said pad A and terminates in a downward portion j, which portion has its opposite sides beveled outwardly to fit within a dovetailed central portion k of the saddle-tree, as seen in Fig. 5, and the arm D is rigidly secured to the saddle-tree by a screw l, which is made to enter the dovetailed portion of the same.

The pads A' A', which form the seat proper, are each of a circular form and constructed somewhat similar to the pommel-pad A, with the exception that a centrally-circular recess m is provided to extend partially through the felt f from the bottom of each of the said pads A' A' to receive a spiral spring n, by which a more yielding cushion is obtained than is required for the pommel-pad. These two pads A' A' are placed within metallic cup-shaped holders o o, each of which have a side flange to surround the pads, as h h, and the said pads are secured to the said cup-holders by screw-bolts i i, as hereinbefore described. Each of the holders o o has a centrally-projecting ear h', provided with a screw-threaded opening h² (see Fig. 6) to engage upon either end of the screw-threaded portions of the bolt C, and which bolt by turning the collar e' moves the said pads to the position required by the

rider, and when so adjusted apart from each other the extensions c^3 c^3 of the saddletree B form stops for the ears h' h' to abut against in the backward swing of the said pads.

5 E is a flat cross-bar centrally mounted upon a bolt q , which is made to enter a screw-threaded opening formed in the pommel-arm D. Said cross-bar is loosely mounted on this bolt and is provided with an elongated slot 10 near each extremity, as r r , and through which slots bolts q' q' project and enter screw-threaded openings formed in the bottom of the cup-holders o o. The function of the cross-bar E is to permit of more or less forward 15 swing of the pads A' A', and this adjustment is obtained by simply unscrewing the bolts q and q' a trifle, which allows the cross-bar to drop to the position as indicated in dotted lines in Fig. 3, and each alternate movement 20 of the rider when seated causes the cross-bar E to tilt, and which bar permits of greater forward swing of the pads, as shown by dotted lines in said Fig. 3.

It will be readily understood that by my 25 construction this saddle contains in itself all that is necessary to allow of quick lateral adjustment in bringing the centers of the rear pads directly under the position of the pelvis-bones and at the same time by having the 30 said pads mounted as described allows the pads to swing with the movements of the rider.

Having described my invention, what I claim is—

35 1. In a bicycle-saddle, the combination, of a saddletree, made in one piece of metal adapted to extend transversely across the saddle-post, having an ear projecting upwardly near each extremity thereof, each of which 40 ears is provided with an opening opposite to each other, and an outer extension from the upper portion of each of said ears, and parallel with the openings of the same, said saddletree being also provided with a central 45 transverse groove, a bolt mounted in the ears of said saddletree and provided with a right and left hand screw-threaded portion at either

end thereof, a circular collar rigidly secured upon the central portion of said bolt and made to fit in the said groove of the saddletree, two circular pads made of yielding material, as described, metallic holders for said pads each having a projecting ear provided with a transverse screw-threaded opening to receive the threaded portion of said bolt, a 50 pommel-arm rigidly secured to the said saddletree, with means secured upon said arm for permitting limited forward swing to the said pads, as shown and described.

2. In a bicycle-saddle, the combination, of 55 a saddletree cast in one piece and adapted to extend transversely across the saddle-post, centrally secured thereon and having vertical ears near each extremity thereof, each of said ears provided with a circular opening opposite to each other, and an extension from each of said ears of the saddletree, said saddletree being also provided with a central transverse groove, a bolt mounted in the openings of 60 the ears of said saddletree and provided with 65 right and left hand screw-threaded portions, a circular collar rigidly secured centrally of the said bolt and adapted to rotate in the groove of said saddletree, two metallic cup-shaped holders each having a centrally-projecting ear provided with a screw-threaded 70 opening to engage the threaded portion of said bolt, a yielding pad secured in each of the said holders, a centrally-projecting pommel-arm rigidly secured to the said saddle- 75 tree and provided with a yielding pad, a screw-threaded bolt in said arm, a cross-bar loosely mounted on said bolt and provided with a slotted opening near each extremity thereof, with a screw-threaded bolt in each 80 of the openings of said cross-bar to engage in the bottom of said holders, as shown and described.

In testimony whereof I affix my signature in presence of two witnesses.

GEORGE A. MEIGHAN.
